UNITED STATES PATENT OFFICE.

ANDREW FORSTER, OF COWES, ISLE OF WIGHT, ENGLAND, ASSIGNOR TO J. SAMUEL WHITE & COMPANY, LIMITED, OF EAST COWES, ISLE OF WIGHT, ENGLAND.

SLOTTING-MACHINE.

1,294,646.

Specification of Letters Patent. Patented Feb. 18, 1919.

Application filed July 15, 1918. Serial No. 244,928.

To all whom it may concern:

Be it known that I, ANDREW FORSTER, a subject of the King of England, and residing at Cowes, Isle of Wight, in England, 5 have invented certain new and useful Improvements in Slotting-Machines, of which the following is a specification.

This invention relates to slotting machines and has for its object to provide a 10 machine which is more especially adapted for operating on a semi-cylindrical or otherwise curved object wherein the slotting is to be performed in conformity with the curvature of the object and to enable 15 undercut or inclined surfaces to be dealt with.

In the construction of parts of some mechanisms such for example as the casings of certain types of steam turbines it is necessary 20 to slot out ports in the end portion of a semi-cylindrical member and these ports have to be cut on the curve and are usually undercut. This slotting operation has hitherto been carried out by hand and is 25 commonly not easy to perform with the necessary accuracy and finish especially where as may be the case the ports are positioned near the main wall of the casing. By means of the present invention the slotting 30 can be effected accurately and expeditiously while the tool can be inclined to a variable extent in order to adjust the angle of undercut as desired to meet requirements.

According to this invention a reciprocating 35 tool box is pivotally suspended so that the direction of the tool stroke can be varied and this tool box carries a member so formed that a block which lies in a guide therein can both reciprocate and also oscillate about a longitudinal axis. A power driven shaft is provided having a crank pin which engages and can slide freely in the sliding block at right angles to the direction in which the block slides in its guide 40 and by means of this shaft and crank pin the tool holder is reciprocated irrespective of the angular adjustment of the tool box. The guide carried by the tool holder is wholly or partially cylindrical and prefer- 45 ably formed in the body of the holder the block which lies in this guide being of suitable dimensions and so constructed as to permit of its oscillation about the axis of the guide as well as reciprocating therein. 50 The axis of the power driven crank shaft 55

lies at right angles to the axis of the cylindrical guide and the crank pin which is preferably carried on a disk or otherwise formed or mounted on the end of the power shaft passes through openings in the side 60 of the tool box and in the tool holder and engages the block in the guide in such a manner that this block can slide freely on the crank pin. The tool box is suspended from a member pivotally carried on a frame 65 which is so constructed and arranged that it can be mounted on or fixed to the work when the member which carries the tool box can be swung with relation to the work about its pivot center. The power driven shaft is 70 disposed radially with relation to this pivot center so that the tool can be swung into any position about this center and slotting performed thereby on an arc of a circle of which the pivot on the frame is the center. 75 At the same time by adjusting the tool box about its point of suspension the direction of the tool stroke can be varied so that undercutting can be performed. In addition to movement about its pivot center the member 80 which carries the tool box and the power shaft can be adjusted radially with respect to this center both for the purpose of feeding the tool to its work in the radial direction and also to enable the tool to be operative 85 on parts whose radius of curvature is different. The screw adjustment is conveniently provided for purposes of feed and radial adjustment of the tool within certain limits. For greater variations in the operating 90 radius of the tool the power shaft can be changed for one of greater or less length the member carrying the shaft of the tool box being so formed that its radial length can be varied to a corresponding extent. 95

Power is preferably obtained from an electric motor mounted on the member which carries the shaft and tool box the motor being connected by suitable gearing to the shaft. Alternatively power may be conveyed to the shaft through a flexible shaft, or a compressed air motor may be employed.

The frame which carries the whole machine is conveniently of girder type and of such construction and dimensions as to permit of its being attached to the work on which the slotting operation is to be performed by bolting the frame through this work or otherwise mounting the machine in fixed relation to the work. 105 110

The accompanying drawings illustrate by way of example one construction of the improved slotting machine showing it as being employed on a portion of the casing of 5 a steam turbine. In these drawings,

Figure 1 is a plan of the slotting machine showing it bolted in position on the work, the driving motor being omitted.

Fig. 2 is a central vertical section through 10 the machine taken on the line 2—2 of Fig. 1 the driving motor being here shown in place.

Fig. 3 is an end elevation of the machine viewed from the right hand side of Fig. 1 the electric motor being omitted.

15 Fig. 4 is an elevation of the tool box end of the machine the motor being omitted.

Fig. 5 is a section of the tool box taken on the line 5—5 of Fig. 2 and looking in the direction of the arrows.

20 Like letters indicate like parts through out the drawings.

A frame member A of suitable length and construction carries in the center of its length a bed plate B provided on its under 25 side with a pivot pin B' which lies in a corresponding hole A' in the frame A. The bed plate B carries on its underside about the pivot pin B' a worm wheel B² with which gears a worm A² suitably fixed on the frame.

30 A and provided with some convenient means for rotating it. By means of this worm A² and the wheel B² the bed plate B can be swung into any position about its pivot B' on the frame A. The upper part of the bed

35 plate B is formed as a slide B³ on which rests a member or casing so as to be movable on the slide in a radial direction with relation to the pivot B'. This member is formed of two parts C and D suitably connected to

40 together by bolts or otherwise. The part C forms the main portion of the member and comprises a downwardly directed portion C' which rests on and engages the slide B³ a main body portion and an upper plate C²

45 on which is mounted an electric motor E. The part D is bolted to one end of the part C and comprises a downwardly directed portion D' shaped to engage the slide B³ and a lug D² on its upper part which over-

50 hangs the end of the part D. A feed screw F is carried at its ends by the parts C' and D' and this screw passes through and engages a correspondingly screw-threaded block G mounted on the end of a spindle G'

55 which passes downwardly through the pivot pin B'. One end F' of the screw F is squared to permit of the screw being rotated in some convenient manner for the purpose of moving the member or casing C D in a

60 radial direction with relation to the pivot B'. The member C D is formed hollow about its center portion and has its ends constructed as bearings which carry a power shaft H. On that end of the shaft which

65 projects beyond the part D is a disk H² pro-

vided with a crank pin H². On the opposite end of the shaft H which projects beyond the part C is mounted a gear wheel H³.

The tool box J is provided at its upper part with two lugs J' and a pin K is passed

70 through these lugs and through the lug D² so that the tool box is thereby pivotally suspended from the part D. Within the tool

75 box is mounted a member which forms part of or to which is fixed the tool holder M.

The member L can move vertically in the tool box J so as to impart the necessary reciprocating movement to the tool M'. The

interior of the member L is hollowed out to constitute a cylindrical guide L' the axis

80 of which lies in or about the same plane as but at right angles to the portions of the tool

box J which serve to guide the member L in its reciprocating movement. In this cylin-

85 drical guide L' lies a block N shaped so that it can both reciprocate in the guide L' and

also oscillate therein about the axis of this

cylindrical guide. An opening L² is formed

in the rear side of the guide member L and

90 through this opening passes the crank pin H² which so engages the sliding block N that

the crank pin can slide freely in and out of

the block N. Thus as the shaft H rotates

95 the crank pin will cause the block N to

reciprocate in the guide L' while the guide

member L will be caused to reciprocate in

the tool box J thereby imparting the neces-

swung into any position about its pivot B' on

the frame A. The upper part of the bed

100 plate B is formed as a slide B³ on which

rests a member or casing so as to be movable

slide in the block N, reciprocation can be

imparted to the block N and to the guide

member L respectively by the crank pin

105 H² irrespective, within reasonable limits, of

the angular position of the tool box J about

its pivot K. Thus without alteration or af-

fecting the operation of the machine the

position of the tool box J can be adjusted

about the pivot K so as to vary the direction

110 of the tool stroke. This angular adjustment

is conveniently effected by means of arms

or pins O which are carried by and project

from the back of the tool box J. These

arms O are clamped or fixed by screws in

some suitable manner to lateral lugs D³

115 formed on the part D.

Power is transmitted from the electric

motor E to the shaft H by suitable gearing

which may comprise as in the construction

120 illustrated a pinion E' on the motor shaft

which gears with a toothed wheel P mounted

on one end of a lay shaft P' on the other end

125 of which is a pinion P² which gears with

the toothed wheel H² mounted on the end

of the shaft H.

The machine is shown in the drawings as

being arranged to slot out ports Q formed

in the end portion Q' of one half of a tur-

bine casing Q². When placed in position the

frame member A is bolted to the flanges Q³

130.

of the turbine casing when the pivot B will lie with its axis coincident with the axis of the casing. The position of the tool is then radially adjusted by means of the feed screw 5 F and by means of the arms O and the angle of inclination of the tool box J is set in accordance with the direction in which the tool strokes are to be taken in order to undercut the ports Q in the desired manner as 10 shown in Fig. 2. By means of the worm A² and wheel B² the machine can be swung into position so as to operate in succession on each of the ports Q and by means of the worm A² the tool is fed to its work in a circumferential direction about the pivot B'. 15 The feed for the depth of cut is effected by the screw F. It will be seen that with this machine the slotting of all the ports Q can be effected truly on arcs struck from the 20 axial center of the casing and accuracy in the dimensions of the ports and similar undercutting in each port can be insured. It is obvious that the tool may be set to slot out either side of each port and by suitable angular adjustment of the tool box the two opposite walls of the port or passage Q can be undercut the strokes being inclined in opposite directions. 25

The details of construction may be varied 30 to meet requirements and the nature of the work on which the machine is intended to operate. If it is desired to increase the radial distance of the tool from the pivot B' the part D is disconnected from the main 35 portion of the casing member C and the shaft H and screw F removed. Another and longer screw F and a longer shaft H can then be substituted and a filling piece inserted between the parts D and C so as to increase the distance between the bearings for 40 the shaft H. The manner of transmitting power to the shaft H may also be varied. Thus for example some flexible power transmitting device may be employed. The manner 45 of mounting the machine may be modified as for instance where it is not desirable or convenient to attach the machine to the work in the manner described. The machine may be suitably fixed or mounted on 50 a bed plate while the work is attached thereto in some convenient manner. Where the work is constituted by some piece of mechanism which is not semi-cylindrical but comprises a portion upon which slotting is to be 55 performed over an arc of a circle the machine may be suitably mounted in relation to the work so as to bring the pivot B' truly at the center from which the curve of the work is struck. 60

It is to be noted that by means of this machine slotting can be performed on ports which are positioned as are the ports Q in close relation to the main wall Q² of the casing where it would be difficult or impossible

to effect the slotting separately by hand owing to proximity to the part Q². 65

What I claim as my invention and desire to secure by Letters Patent is:—

1. In a slotting machine the combination of a supporting member, a tool box pivotally suspended from this member, means for adjusting and setting the tool box about its pivot relatively to the supporting member, a tool holder mounted so as to reciprocate in the tool box, a rotatable shaft carried 70 by the supporting member, a crank pin on one end of this shaft which engages the tool holder and operates to reciprocate it in the tool box as the shaft rotates, and means for imparting rotation to the shaft as set forth. 75

2. In a slotting machine the combination of a frame member, a supporting member pivotally mounted on the frame member, a tool box pivotally suspended from the supporting member, means for adjusting and 80 setting the tool box about its pivot relatively to the supporting member, a tool holder mounted so as to reciprocate in the tool box, a rotatable shaft carried by the supporting member, a crank pin on one end of this shaft 85 which engages the tool holder and operates to reciprocate it in the tool box as the shaft rotates, and means for imparting rotation to the shaft as set forth. 90

3. In a slotting machine the combination 95 of a supporting member, a tool box pivotally suspended from this member, means for adjusting and setting the tool box about its pivot relatively to the supporting member, a tool holder mounted so as to reciprocate 100 in the tool box, a block formed and mounted so that it can both reciprocate and oscillate in the tool holder, a rotatable shaft carried by the supporting member, a crank pin on one end of this shaft which engages the block 105 within the tool holder and operates to reciprocate the tool holder in the tool box as the shaft rotates, and means for imparting rotation to the shaft as set forth. 110

4. In a slotting machine the combination 115 of a frame member, a supporting member pivotally mounted on the frame member, a tool box pivotally suspended from the supporting member, means for adjusting and setting the tool box about its pivot relatively to the supporting member, a tool holder mounted so as to reciprocate in the tool box, a block formed and mounted so that it can both reciprocate and oscillate in the tool holder, a rotatable shaft carried by the supporting member, a crank pin on one end of this shaft 120 which engages the block within the tool holder and operates to reciprocate the tool holder in the tool box as the shaft rotates, and means for imparting rotation to the shaft as set forth. 125

5. In a slotting machine the combination of a frame member, a supporting member

- 5 pivotally mounted on the frame member, a tool box pivotally suspended from the supporting member, means for adjusting and setting the tool box about its pivot relatively to the supporting member, a tool holder mounted so as to reciprocate in the tool box, a rotatable shaft carried by the supporting member and disposed radially with respect to the pivot of this member, a crank pin 10 on one end of this shaft which engages the tool holder and operates to reciprocate it in the tool box as the shaft rotates, and means for imparting rotation to the shaft as set forth.
- 15 6. In a slotting machine the combination of a frame member, a supporting member pivotally mounted on the frame member and adjustable thereon radially with relation to the pivot, means for adjusting the supporting member both angularly and radially on the frame member, a tool box pivotally suspended from the supporting member, means for adjusting and setting the tool box about its pivot relatively to the supporting member, a tool holder mounted so as to reciprocate in the tool box, a rotatable shaft carried by the supporting member, a crank pin 20 on one end of this shaft which engages the tool holder and operates to reciprocate it in the tool box as the shaft rotates, and means for imparting rotation to the shaft as set forth.
- 25 7. In a slotting machine the combination of a supporting member, a tool box pivotally suspended from this member, means for adjusting and setting the tool box about its pivot relatively to the supporting member, a tool holder mounted so as to reciprocate in the tool box, a cylindrical guide in the 30 tool holder, a cylindrical block disposed in this guide so that it can both reciprocate and also oscillate therein, a rotatable shaft carried by the supporting member, a crank pin on one end of this shaft which engages a transverse hole in the cylindrical block and operates to reciprocate the tool holder in the tool box as the shaft rotates, and means for imparting rotation to the shaft as set forth.
- 35 8. In a slotting machine the combination of a supporting member, a tool box suspended by a horizontal pivot from this member, means for adjusting and setting the tool box about its pivot relatively to the supporting member, a tool holder mounted so as to reciprocate in the tool box, a rotatable shaft carried by the supporting member and disposed horizontally and at right angles to the pivot of the tool box, a crank pin on the end of this shaft which is adjacent to the 40 tool box this pin engaging the tool holder and operating to reciprocate it in the tool box as the shaft rotates, and means for imparting rotation to the shaft as set forth.
- 45 9. In a slotting machine the combination of a frame member adapted to be attached to the work operated on, a supporting member pivotally mounted on the frame member, a tool box pivotally suspended from the supporting member, means for adjusting and setting the tool box about its pivot relatively to the supporting member, a tool holder mounted so as to reciprocate in the tool box, a rotatable shaft carried by the supporting member, a crank pin on one end of this shaft which engages the tool holder and operates to reciprocate it in the tool box as the shaft rotates, a power motor mounted on the supporting member, and gearing between this motor and the crank shaft as set forth.
- 50 10. In a slotting machine the combination of a frame member, a supporting member pivotally mounted on the frame member and adjustable thereon radially with relation to the pivot, means for adjusting the supporting member both angularly and radially on the frame member, a tool box pivotally suspended from the supporting member, means for adjusting and setting the tool box about its pivot relatively to the supporting member, a tool holder mounted so as to reciprocate in the tool box, a block formed and mounted so that it can both reciprocate and oscillate in the tool holder, a rotatable shaft carried by the supporting member and disposed radially with respect to the pivot of this member, a crank pin on one end of this shaft which engages the block within the tool holder and operates to reciprocate the tool holder in the tool box as the shaft rotates, and means for imparting rotation to the shaft as set forth.
- 55 11. In a slotting machine the combination of a frame member, a supporting member pivotally mounted on the frame member and adjustable thereon radially with relation to the pivot, means for adjusting the supporting member both angularly and radially on the frame member, a tool box pivotally suspended from the supporting member, means for adjusting and setting the tool box about its pivot relatively to the supporting member, a tool holder mounted so as to reciprocate in the tool box, a cylindrical guide in the tool holder, a cylindrical block disposed in this guide so that it can both reciprocate and also oscillate therein, a rotatable shaft carried by the supporting member, a crank pin on one end of this shaft which engages a transverse hole in the cylindrical block and operates to reciprocate the tool holder in the tool box as the shaft rotates, and means for imparting rotation to the shaft as set forth.
- 60 12. In a slotting machine the combination of a frame member, a supporting member pivotally mounted on the frame member and adjustable thereon radially with relation to the pivot, means for adjusting the

- supporting member both angularly and radially on the frame member, a tool box suspended by a horizontal pivot from the supporting member, means for adjusting and setting the tool box about its pivot relatively to the supporting member, a tool holder mounted so as to reciprocate in the tool box, a block formed and mounted so that it can both reciprocate and oscillate in the supporting member both angularly and radially on the frame member, a tool box pivotally suspended from the supporting member, means for adjusting and setting 30 the tool box about its pivot relatively to the supporting member, a tool holder mounted so as to reciprocate in the tool box, a cylindrical guide in the tool holder, a cylindrical block disposed in this guide so that it can 35 both reciprocate and also oscillate therein, a rotatable shaft carried by the supporting member, a crank pin on one end of this shaft which engages a transverse hole in the cylindrical block and operates to reciprocate 40 the tool holder in the tool box as the shaft rotates, a power motor mounted on the supporting member, and gearing between this motor and the crank shaft as set forth.
- 10 the tool holder, a rotatable shaft carried by the supporting member and disposed horizontally and at right angles to the pivot of the tool box and also radially with respect to the pivot of the supporting member, a 15 crank pin on the end of this shaft which is adjacent to the tool box this pin engaging the block within the tool holder and operating to reciprocate the tool holder in the tool box as the shaft rotates, and means for imparting rotation to the shaft as set forth.
13. In a slotting machine the combination of a frame member adapted to be attached to the work operated on, a supporting member pivotally mounted on the frame member and adjustable thereon radially with 20 relation to the pivot, means for adjusting 25
